GAS BURNER, INCLUDING PRIMARY AND
SECONDARY AIR PREHEATER

Toimi A. Nissinen, Dobbs Ferry, N. Y.

Application December 18, 1945, Serial No. 635,748

2 Claims. (Cl. 158—108)

1

The present invention relates to improvements in gas burners and the like used for heating, and has for its main object the provision of a novel and advantageous form of burner for gaseous material.

Another object of the invention is to provide a novel and advantageous burner for burning gases mixed with preheated air.

Yet another object is to provide a burner for an air and gas mixture wherein air is heated by the burner itself preparatory to its admixture with the gas.

A further object of the invention is to provide a burner for an air and gas mixture, having a plurality of parallel ducts provided with burner jets and one of said ducts being used to heat a duct supplying air for mixture with the gas.

A still further object of the invention is to provide a gas burner of the general character specified, having provisions to prevent back-firing.

A yet further object of the invention is to provide a novel and advantageous burner wherein the temperature maintained adjacent the discharge jets assures ignition of the air and gas mixture and complete combustion thereof.

According to a preferred embodiment of the invention the burner comprises parallel jet tubes closed at one end and at the other end connected to the bottom of a mixing chamber.

Above the central jet tube and heated by the burning gases rising therefrom, is an air supply tube supplying air under relatively low pressure to the upper part of said mixing chamber. The air is mixed with the gas in the mixing chamber and the mixture passes downwardly and into the adjacent ends of the jet tubes which are closed at their other ends. The jets of the burning gas-and-air mixture project upwardly from the central jet tube and impinge on the air supply tube, thereby raising the same to a high temperature as well as the air flowing therethrough.

Above each jet tube at a side of the central jet tube is a refractory body or baffle which may be a half tube of heat resistant material, such as a suitable alloy steel. Said baffle may, advantageously, be made of vanadium steel.

The jets of flame or burning gases from the jet tubes at the sides, strike the refractory bodies and are deflected against the air duct over the central jet tube or through the throat between the air duct and the baffles. Due to the general arrangement described, the high portion of the air supply duct and the air therein may be raised to temperatures of the order of 800° F.

2

The jets of air and gases flowing from the burner or jet tubes may pass through nozzles in the form of tubes secured in openings in the jet tubes and flattened at their outlet ends to provide outlets in the form of slits and prevent back-fire. Said slits extend longitudinally of the burner or jet tubes and determine the direction of the jet.

It is clear that the advantages of my improved burner may be attained whether the pipes or tubes are bent into circular or other form or are straight as shown.

Other features, objects and advantages will appear upon consideration of the following detailed description and of the drawings, in which:

Fig. 1 is a side elevation partly in section, illustrating one embodiment of the invention;

Fig. 2 is a top plan view of the device of Fig. 1;

Fig. 3 is an end elevation as seen from the right 20 of Fig. 1;

Fig. 4 is an enlarged view of a nozzle such as used in the outlets of the jet tubes; and

Fig. 5 is a sectional view taken in the plane of the line 5—5 of Fig. 1.

Referring to the drawings, the burner is illustrated as comprising a vertically arranged mixing chamber 10, a central burner or jet tube 11 arranged horizontally and connected at one end to the lower part of the mixing chamber, the other end being closed as by a cap 12. At opposite sides of the central jet tube 11 are jet tubes 13 parallel to tube 11 and in the same horizontal plane. Each of these tubes has at its upper side outlet openings in which are secured the lower ends of jet nozzles 14 round at their lower ends and flattened at the top to provide an outlet opening in the form of a narrow slit 15 extending longitudinally of the tube. Each tube 13 is connected at one end to the mixing chamber 10 by means including an elbow 16, and is closed at its other end as by means of a cap 12.

Gas is supplied to the mixing chamber 10 by means of a tube or duct 17 passing downwardly through the top or top closure 18 of the mixing chamber and having a perforated downwardly-directed head 19. Air may be supplied to the mixing chamber 10 at a relatively low pressure, by means of a fan 20 supplying air at low pressure to the left end (Fig. 1) of a horizontal air duct or tube 21 beneath the central burner tube 11. From the other end of tube 21, the air passes through an elbow 22 into an upright tube 23, and from the upper end of said tube 23 through an elbow 24 to a horizontally arranged upper tube 25 or duct 25 extending above the central burner

or jet tube 11 and discharging the air thus heated into the upper part of the mixing chamber 10. Due to the arrangement of the outlet slots 15 longitudinally of the burner tube 11, the duct or tube 21 will be heated substantially uniformly throughout its length. Thus the air is hot when it enters the mixing chamber and higher heating efficiency is attained than would be by mixing cold air with the gas and cooling the flame as heretofore.

In order to utilize the heat from the burner to greater advantage, provision may be made for refractory members or bodies against which the flames or jets of burning gases from the burner or jet tubes 13 impinge. Preferably, said refractory bodies which serve as baffles are in the form of half tubes 26 which may be made of a suitable heat-resisting alloy such as vanadium steel. The half tubes 26 may be supported from the base or from the other tubes by any well known means. In impinging against the baffles 26, the jets of flame or burning gases are deflected and a part thereof impinges against the overhead air pipe 25 and acts to heat the air therein and the burning gases are directed through the throat between the air duct 25 and the baffles. It will be evident that the air in pipe 25 would be heated even if the central burner tube 11 were omitted. However, with the heating of the air by both the central burner tube 11 and the other burner tubes 13, very efficient results may be attained.

While it is possible to secure good results by supplying all of the pre-heated air for combustion through the jet tubes, it is preferable to supply only some of the air through the jet tubes and to supply pre-heated secondary air to the burning gas mixture adjacent the jet nozzles. Such secondary pre-heated air is preferably taken from the air heating duct 25 through holes or nozzles 27 so located and directed as to discharge pre-heated air into the zone of initial combustion just beyond the nozzles 14. The secondary air induces considerable turbulence which mixes the gases and results in practically complete combustion. By taking both primary and secondary air from the same duct they can be controlled simultaneously and in proper relation to the gas flow.

The intimate mixture of gas and air, with consequent increase in completeness of combustion, is greatly enhanced by the arrangement of the baffles relatively to the gas and air outlets. The secondary air discharging into the zone of the jets, coupled with the deflection of the gases by the deflectors 26, causes turbulence and directs the mixture not only toward the air duct 25 to assure preheated air, but also through the throats formed by the baffles and the duct 25. The baffles are soon raised to the kindling temperature of the gas mixture, thus further assuring a high degree of completeness of combustion.

The apparatus herein disclosed attains much greater efficiency than heretofore and gives not only a hotter flame but also substantially perfect combustion.

An important advantage in using the alloy steel half tubes 26 as the refractory members or baffles is that they heat up rapidly and therefore avoid,

at the beginning of a heating operation, the chilling of the jets of flame and incomplete combustion which would otherwise occur, and the consequent falling-off of efficiency in heating. The baffles 26 very quickly become hot and assure combustion of the gas mixture impinging thereon.

Even if the low pressure blower 20 were omitted, the burner would function and the action would be more or less like that of a Bunsen burner, with the advantages, however, of pre-heated air.

It should be understood that various changes may be made and that various features may be used without others, without departing from the true scope and spirit of the invention.

I claim:

1. In a gas burner, a burner conduit including generally upwardly directed gas jets, an air conduit connected to said burner conduit for conducting primary air to said burner conduit for mixing with gas therein, said air conduit being positioned generally above and to one side of said gas jets, refractory baffle means immediately adjacent said jets and having a deflecting surface inclined to intercept burning gases from said jets and to deflect them toward said air conduit, said air conduit being adjacent but slightly spaced from said baffle means so as to define a throat between said air conduit and said baffle means, said air conduit having openings positioned to discharge preheated secondary air toward said throat and into the burning zone of burning gas from said jet.

2. A gas burner comprising a mixing chamber, a horizontally extending burner tube connected at one end to said mixing chamber, means for supplying air to said mixing chamber including an air supply pipe connected thereto and located above the level of and parallel to said burner tube, means for supplying gas to said mixing chamber, said burner tube having burner outlets along the top thereof, and a baffle located above said burner outlets and positioned to direct flames from said burner outlets onto said air supply pipe for heating air therein whereby preheated air may be supplied to said mixing chambers, said air supply pipe having a plurality of air outlets along the under side thereof for supplying secondary air to the gas from said burner outlets of said burner tube.
